UNITED STATES PATENT OFFICE.

ERNEST RORABACK, OF SPRINGFIELD, MASSACHUSETTS.

SHOE-CREASING DEVICE.

SPECIFICATION forming part of Letters Patent No. 744,620, dated November 17, 1903.

Application filed July 23, 1903. Serial No. 166,739. (No model.)

To all whom it may concern:

Be it known that I, ERNEST RORABACK, a citizen of the United States of America, residing at Springfield, in the county of Hampden and State of Massachusetts, have invented new and useful Improvements in Shoe-Creasing Devices, of which the following is a specification.

This invention relates to devices for creasing the vamps of shoes. Heretofore this creasing has been done at the factory, machines being provided for that purpose whereby the vamps may be pressed between dies to effect it. All purchasers, however, do not desire creased vamps; and the object of this invention is to provide a hand-operated device for use in shoe-stores for creasing the vamps of the shoes after they are made; and the invention consists in a grooved or fluted plate secured to one jaw of a pair of short tongs, to the other jaw of which is secured a frame-like structure fitting over two sides of said plate to stretch the leather more or less over the grooved surface thereof. The creasing may then be done with a button-hook or other smooth round-ended instrument.

In the drawings forming part of this application, Figure 1 is a sectional elevation of a shoe, showing the creasing device, partly in section, in operative position therein. Fig. 2 is a perspective view of the forward end of the device. Fig. 3 is a cross-section through the end of the device and the shoe, taken in the plane of line 3-3, Fig. 1. Fig. 4 is a side elevation of a fluted roll.

Referring now to the drawings, *a* indicates the vamp of a shoe, and *b* one of the jaws of the tongs, *c* indicating the other. These jaws are united at *d* and provided with suitable handles *e* and *f*.

On the end of the jaw *b* is a grooved or fluted plate *g*, the flutes *h* being transversely located therein. These flutes have rounded contours when seen in cross-section, as in Fig. 1. Preferably this plate is made integral with the jaws *b*; but this is not essential. On the under side of the plate *g* is a boss *i*, which is tapped and threaded to receive a threaded knob *j*.

On the jaw *c* there is formed a rectangular three-sided frame-like structure *k*, the opposite sides of which, parallel with the jaw *c*,

fit over the two like sides of the plate *g*, the inner surfaces of these sides of the frame being more or less beveled, as shown in cross-section and in Fig. 3 and also shown in Fig. 2. The effect of thus beveling the sides of the frame *k* is to stretch the vamp *a* more or less tightly over the plate *g* and in the direction of the lengthwise dimensions of the flutes *h*. This tends naturally to draw the vamp down into the grooves, and the frame *k*, fitting well down over the plate, as shown in Fig. 3, will leave that portion of the vamp to be creased above the top of the frame *k*, thereby permitting the use of a button-hook or some similar instrument which will not scratch the leather to force the leather by rapid reciprocatory movements into the flutes. This is the more convenient way, though, if desired, a fluted roll, mounted in a frame with a suitable handle, may be used; such as is shown in Fig. 4. By holding the leather along each side of the block in the manner described all of the slack which is necessary to form the creases in the vamp will be supplied by the drawing in of the leather over either end of the plate *g*.

Preferably between the handles *e* and *f* of the tongs the ratcheted post *m* is located, being pivoted to one of the handles and passing through a slot in the other, one lip *n* of said slot being formed to engage the ratchet teeth *o* in the edge of the post. This particular method of securing the handles together, however, does not constitute an essential feature of the invention. Some other device may, if desired, be substituted for it.

During the crease-forming process it is of course necessary that the plate *g* should be supported firmly against the sole of the shoe, and as this creasing device must be used on shoes of different sizes the knob *j* is provided, which may be screwed in or out to provide a proper support for the plate.

The frame *k* may be provided with notches *p* or other suitable marks to denote the location of the flutes in the plate *g*.

Having thus described my invention, what I claim, and desire to secure by Letters Patent of the United States, is—

1. Creasing-tongs having two jaws, a plate on one of the jaws having flutes therein extending transversely of a shoe, a frame-like structure located on the other jaw and ar-

ranged to fit over the sides of said plate at which the flutes terminate; said plate and frame being arranged to grasp the vamp of the shoe.

- 5 2. Creasing-tongs having two jaws arranged to grasp the vamp of the shoe between them, a plate on one of the jaws having a transversely-fluted upper surface, a frame-like structure on the other jaw, arranged to fit over opposite sides of said plate, and an adjustable abutment for the latter.
- 10 3. Creasing-tongs having two jaws arranged

to grasp the vamp of the shoe between them, a plate on one of the jaws having transverse flutes in the upper surface thereof; a frame-like structure located on the other jaw arranged to fit over opposite sides of said plate to draw the vamp more or less into said flutes, and means to lock the jaws together. 15
